Primary Examiner — Eric L Goodman*Assistant Examiner* — Sarah L Smith(74) *Attorney, Agent, or Firm* — Alston & Bird LLP(57) **CLAIM**

The ornamental design for a flashlight, as shown and described.

DESCRIPTION

FIG. 1 is a top front perspective view of a flashlight according to one exemplary embodiment of the present design.

FIG. 2 is a bottom rear perspective view of the flashlight of FIG. 1.

FIG. 3 is a front view of the flashlight of FIG. 1.

FIG. 4 is a back view of the flashlight of FIG. 1.

FIG. 5 is a top view of the flashlight of FIG. 1.

FIG. 6 is a bottom view of the flashlight of FIG. 1.

FIG. 7 is a left side view of the flashlight of FIG. 1; and, FIG. 8 is a right side view of the flashlight of FIG. 1.

The broken lines are directed to unclaimed features of the flashlight and form no part of the claimed design.
